Samuel Burrows, Chicago, Ill., assignor to Neo
Products Co., Chicago, Ill., a corporation of
Illinois

Application September 16, 1953, Serial No. 26,831

Term of patent 3½ years

(Cl. D61—1)

To all whom it may concern:

Be it known that I, Samuel Burrows, a citizen of the United States, residing at Chicago, in the county of Cook and State of Illinois, have invented a new, original, and ornamental Design for a Combined Photo Frame and Shadow Box or Similar Article, of which the following is a specification, reference being had to the accompanying drawings, forming part thereof.

Fig. 1 is a top plan view of a combined photo frame and shadow box or similar article, showing my new design;

Fig. 2 is a front elevational view thereof;

Fig. 3 is a bottom plan view thereof;

Fig. 4 is a rear elevational view thereof; and
Fig. 5 is an end elevational view thereof.

I claim:

The ornamental design for a combined photo frame and shadow box or similar article, substantially as shown.
